UNITED STATES PATENT OFFICE.

JOHN R. O'DONNELL, OF NEW YORK, N. Y.

BAR-CHAIR USED IN CONCRETE CONSTRUCTION.

1,178,939.

Specification of Letters Patent. Patented Apr. 11, 1916.

Application filed August 18, 1915. Serial No. 46,050.

To all whom it may concern:

Be it known that I, JOHN R. O'DONNELL, a citizen of the United States, residing in the borough of Brooklyn, city of New York, county of Kings, and State of New York, have invented new and useful Improvements in Bar-Chairs Used in Concrete Construction, of which the following is a specification.

10 This invention relates to means known as bar chairs for supporting and locating in certain predetermined positions, reinforcing bars for concrete construction work.

In all reinforced concrete construction work, the beams and girders are reinforced by bars running lengthwise thereof. These bars are placed in the form before the concrete is poured therein. Usually they are located in the lower part of the beam or girder; and it is frequently essential for the purpose of fireproofing that a certain specified amount of concrete cover the bars. It is likewise essential that the bars be so supported as to limit their possible movement 25 from the bottom of the beam. The bar chairs now and heretofore in use for supporting these reinforcing bars frequently tip and the result is that a workman loses time in relocating the chair; or if the tipping 30 remains undiscovered, the reinforcing bar will not be maintained in correct position; and the bar will not be fireproofed.

The object of my invention is to provide a bar chair that is simple, cheap to manufacture, easy to place in position, non-tippable, and which will accurately position the reinforcing bar in the beam or girder.

For fuller explanation and description, reference is hereby made to the accompanying drawings, of which—

Figure 1 is a vertical section through a section of reinforced concrete construction, showing part of the floor and a beam or girder to which my invention is applied. Fig. 2 is a sectional view taken on the line 2—2 of Fig. 1. Fig. 3 is a vertical cross section of a beam or girder illustrating a method of using my invention. Fig. 4 is a sectional view illustrating a slightly different embodiment of my invention. Fig. 5 is a sectional view showing the floor, beams, girders and columns and the method of applying my invention. Fig. 6 is a perspective view of a form of my improved chair. Fig. 7 is a sectional plan view showing how the chair is located in the form or mold.

Fig. 8 is a perspective view of a chair-flange provided with means for keeping the chair from rolling.

Referring again to the drawings, 10 designates the floor supported by beams 11, girders 12, and columns 13, (Fig. 5). In all concrete construction work, the forms are erected first; and in the drawings, 14 represents the floor form, 15 the side forms for the beam or girder, and 16 the bottom form.

After the forms have been erected the reinforcing bars 17 are placed in position. These bars are adapted to run lengthwise of the beam, some of them running parallel to the bottom of beam as 18 (Figs. 1 and 5) and others 19 are bent so as to bring their ends up near the level of the floor.

To support the bars, I provide an improved chair 20. As shown in Fig. 5, two 75 of these chairs 20 are placed in a span between girders or beams, thus affording the bars a support near each end. These chairs 20 consist of a series of hub portions 21, provided with flanges 22, said hubs 21, being 80 mounted on or made integral with a shaft 23. It is obvious from the drawings that the flange part 22 rests on the bottom form 16 of the beam or girder and the hub portion 21 supports the bars 17. While the 85 drawings show only two bars supported on a line it is understood that a plurality of hubs and flanges may be provided to support any number of bars on the same level. In Figs. 2 and 8 a shoulder 24, having a 90 flat surface to bear upon the form 16, is carried by one of the flanges 22, which acts as a stop to keep the chair from rolling. This stop 24 is not at all essential as will be explained later. The limitation of the 95 movement of the chair may also be secured by the use of hexagonal parts 26 instead of flanges in the form shown in the drawings.

Fig. 3 of the drawings illustrates how a double row of bars may be readily supported by resting a second chair on the lower set of bars.

Fig. 4 shows a slightly different form of my improved chair in which the bars 17, rest directly on a shaft 25 (Fig. 6) and flanges 26 support the chair from the bottom, said flanges 26 resting on the bottom board of the form. Smaller flanges 27 are provided to confine the bar to its proper position.

Fig. 7 shows how the chairs should be placed in the form. It will be noted that

the longitudinal axis of the shaft 25 is slightly skewed off so as not to be at regular angles to the sides 15 of the form. (Of course, if the hexagonal form of flange is employed, it will not be necessary to place the chair in this skewed position.) The result is that if anything happens to make the chair roll slightly the limit of movement would be to the dotted position 28, as one of the ends of the shaft 25 would bind against the side form 15.

Having now described my invention, what I claim as new and desire to secure by Letters Patent is:

15 1. In a bar-chair for concrete construction, a shaft carrying circular flanges spaced apart to permit the disposition of a bar therebetween, one of said flanges being pro-

vided with means for limiting the rolling of the chair.

2. A bar-chair for concrete construction, comprising a shaft, hubs carried thereby, and circular flanges at the ends of said hubs, one of said flanges being provided with means for limiting the rolling of said chair. 25

3. A bar-chair for concrete construction, comprising a shaft, hubs carried thereby, and circular flanges at the ends of said hubs, one of said flanges being provided with a shoulder limiting the rolling of said chair. 30

Signed at New York city, this 11th day of August, 1915.

JOHN R. O'DONNELL.
